13 Claims. (Cl. 194—100)

This invention relates to improvements in Money-Handling Devices. More particularly, this invention relates to improvements in devices which can test and sort coins.

It is, therefore, an object of the present invention to provide an improved device which can test and sort coins.

In the testing and sorting of coins, it is customary to separate coins which are made of coin silver from coins or slugs which are made of metals or alloys that have resistivities materially different from the resistivity of coin silver. For example, it is customary to separate coins which are made of coin silver from coins or slugs which are made of copper, zinc, brass, cupronickel, lead, and German silver. In separating coins which are made of coin silver from such coins or slugs, it is customary to provide magnetic flux lines adjacent a runway, and to provide a deflector and a separator adjacent to, but below the level of, the discharge end of that runway. As a copper coin or slug rolls along the runway, the magnetic flux lines will develop eddy currents within that coin or slug which will generate a magnetic field; and that magnetic field will interact with those magnetic flux lines to reduce the speed of that coin or slug sufficiently to cause it to fall short of the separator, and thus pass to a rejected coin chute. As a zinc, brass, cupronickel, lead or German silver coin or slug rolls along the runway, the magnetic flux lines will develop eddy currents within that coin or slug which will generate a magnetic field; and that magnetic field will interact with those magnetic flux lines and tend to reduce the speed of that coin or slug. However, because of the relatively high resistivities of zinc, brass, cupronickel, lead and German silver, the magnetic field generated by the eddy current in such a coin or slug will not be large enough to cause a material reduction in the speed of that coin or slug. As a result, such a coin or slug will strike the deflector with sufficient force to cause that coin or slug to rebound back past the separator, and to pass into the rejected coin chute. As a silver coin rolls along the runway, the magnetic flux lines will develop eddy currents in that coin which will generate a magnetic field; and that magnetic field will interact with those magnetic flux lines to reduce the speed of that coin sufficiently to enable it to pass between the deflector and separator, and thus pass to an accepted coin chute. As a result silver coins are accepted, whereas copper, zinc, brass, cupronickel, lead and German silver coins or slugs are rejected.

In some instances, however, it is desirable to accept some high resistivity coins as well as silver coins, while rejecting copper, zinc, brass, and lead coins or slugs. Consequently, it would be desirable to provide a coin separator which could accept some high resistivity coins as well as silver coins, but which would reject copper, zinc, brass, and lead coins or slugs. The present invention provides such a coin separator; and it is, therefore, an object of the present invention to provide a coin separator which can accept some high resistivity coins as well as silver coins, but which will reject copper, zinc, brass, and lead coins or slugs.

The coin separator of the present invention provides magnetic flux lines adjacent a runway, and provides a deflector and a separator adjacent to, but below the level of, the discharge end of that runway. As a silver coin

2

rolls along the runway, the magnetic flux lines will develop eddy currents in that coin which will generate a magnetic field; and that magnetic field will interact with those magnetic flux lines to reduce the speed of that coin sufficiently to enable it to pass between the deflector and separator, and thus pass to an accepted coin chute. As a copper coin or slug rolls along the runway, the magnetic flux lines will develop eddy currents within that coin or slug which will generate a magnetic field; and that magnetic field will interact with those magnetic flux lines to reduce the speed of that coin or slug sufficiently to cause it to fall short of the separator, and thus pass to a rejected coin chute. As a zinc or brass coin rolls along the runway, the magnetic flux lines will develop eddy currents within that coin or slug which will generate a magnetic field; and that magnetic field will interact with those magnetic flux lines to reduce the speed of that coin or slug sufficiently to cause it to fall short of the separator, and thus pass to a rejected coin chute. As a zinc or brass coin rolls along the runway, the magnetic flux lines will develop eddy currents within that coin or slug which will generate a magnetic field; and that magnetic field will interact with those magnetic flux lines to reduce the speed of that coin or slug to some extent. However, because of the resistivity of zinc or brass, the magnetic field generated by the eddy currents in such a coin or slug will not be great enough to cause a material reduction in the speed of that coin or slug. As a result, such a coin or slug will strike the deflector with sufficient force to cause that coin or slug to rebound back past the separator, and to pass into the rejected coin chute. As a higher resistivity coin, such as a cupronickel coin, rolls along the runway, the magnetic flux lines will develop eddy currents within that coin which will generate a magnetic field; and that magnetic field will interact with those magnetic flux lines to tend to reduce the speed of that coin. However, because of the relatively high resistivity of that coin, the magnetic field generated by the eddy currents in such a coin will not be great enough to cause an appreciable reduction in the speed of that coin. As a result, such a coin will strike the deflector with sufficient force to cause that coin to rebound back to a second deflector; and that coin will then rebound from that second deflector and pass between the first deflector and the separator, and thus to the accepted coin chute. As a lead coin or slug rolls along the runway, the magnetic flux lines will develop eddy currents within that coin or slug which will generate a magnetic field; and that magnetic field will interact with those magnetic flux lines to tend to reduce the speed of that coin or slug. However, because of the relatively high resistivity of lead, the magnetic field generated by the eddy currents in such a coin or slug will not be great enough to cause an appreciable reduction in the speed of that coin or slug. As a result, such a coin or slug will strike the deflector with substantial force. However, lead is relatively soft; and hence while the lead coin or slug will rebound back from the deflector, it will not reach the second deflector. Instead, that lead coin or slug will rebound back past the separator and pass into the rejected coin chute. In this way, silver and some higher resistivity coins will pass to the accepted coin chute, but copper, zinc, brass, and lead coins or slugs will pass to the rejected coin chute. It is, therefore, an object of the present invention to provide a coin separator which accepts silver and some higher resistivity coins, but which rejects lower resistivity and other high resistivity coins or slugs.

Other and further objects and advantages of the present invention should become apparent from an examination of the drawing and accompanying description.

In the drawing and accompanying description several preferred embodiments of the present invention are shown and described, but it is to be understood that the drawing and accompanying description are for the purpose of illustration only and do not limit the invention and that the invention will be defined by the appended claims.

In the drawing, FIG. 1 is a front elevational view of one embodiment of coin separator that is made in accord-

ance with the principles and teachings of the present invention,

FIG. 2 is a partially broken-away, front elevational view of the coin separator shown in FIG. 1, but it shows the upper cradle of that coin separator in rotated position,

FIG. 3 is a sectional view through part of the coin separator shown in FIG. 1, and it is taken along the broken plane indicated by the broken line 3—3 in FIG. 1;

FIG. 4 is a sectional view through another part of the coin separator shown in FIG. 1, and it is taken along the broken plane indicated by the broken line 4—4 in FIG. 2,

FIG. 5 is a sectional view through yet another part of the coin separator shown in FIG. 1, and it is taken along the broken plane indicated by the broken line 5—5 in FIG. 1,

FIG. 6 is a sectional view through still another part of the coin separator shown in FIG. 1, and it is taken along the broken plane indicated by the broken line 6—6 in FIG. 2,

FIG. 7 is a rear view of a still further part of the coin separator of FIG. 1,

FIG. 8 is a diagrammatic showing of the runway, magnet, deflector, and separator of the coin separator shown in FIG. 1, and it indicates the path which a silver coin will follow,

FIG. 9 is a schematic diagram which is similar to that of FIG. 8, but it indicates the path which will be followed by a hard-surfaced coin with a resistivity higher than the resistivity of coin silver,

FIG. 10 is a schematic diagram which is similar to that of FIG. 8, but it indicates the path which will be followed by a coin having a resistivity lower than the resistivity of coin silver,

FIG. 11 is a schematic diagram which is similar to that of FIG. 8, but it indicates the path which will be followed by coins which have resistivities greater than the resistivity of coin silver but smaller than the resistivity of the coin of FIG. 9,

FIG. 12 is a schematic diagram which is similar to that of FIG. 8, but it indicates the path which will be followed by a lead coin or slug,

FIG. 13 is a schematic diagram of a coin separator which is slightly different from the coin separator shown in FIG. 1, and

FIG. 14 is a schematic diagram of another coin separator which is different from the coin separator shown in FIG. 1.

Referring to the drawing in detail, the numeral 20 denotes the frame of one embodiment of coin separator that is made in accordance with the principles and teachings of the present invention. That frame will be vertically-directed whenever the coin separator is in use; and it has a vertically-directed flange 22 at the left-hand edge thereof and has a vertically-directed flange 24 at the right-hand edge thereof. Those flanges extend forwardly from the plane of the frame 20, and they make that frame generally U-shaped in plan. Pins 26 project outwardly beyond the outer faces of the flanges 22 and 24; and two of those pins are adjacent the top edges of those flanges while the other two of those pins are adjacent the bottom edges of those flanges. Those pins are dimensioned and spaced to enable them to be held by complementary elements on a channel or other supporting structure of a coin changer, vending machine, or other coin-operated device.

A coin-guiding member 27 is secured to, and projects upwardly above, the top edge of the frame 20; and that member has inclined sides which extend forwardly from the plane of FIG. 1. Bosses 28 and 30 extend forwardly from the front face of frame 20; and those bosses are below the level of, but are generally aligned with, the inclined sides of the coin-guiding member 27. As a result, those bosses essentially constitute downward extensions of that coin-guiding member. A shallow, arcuate

recess 32 is provided in the front face of the frame 20 below, but immediately adjacent, the boss 28. A further arcuate recess 34 is provided in the front face of the frame 20; but that recess is disposed to the right of, and at about the same level as, the recess 32. A horizontally-directed slot 36 is provided in the frame 20; and that slot is approximately midway between the upper and lower edges of that frame while being adjacent the flange 24, as shown particularly by FIG. 2. An inclined opening 38 is provided in the frame 20; and that opening is below the level of the slot 36, but it is adjacent the flange 22. Portions of that opening are visible in FIGS. 1 and 2.

A shallow, generally-rectangular recess 40 is provided in the front face of the frame 20; and that recess is disposed below the level of, and to the right of, the opening 38—as shown particularly by FIG. 2. A shallow, horizontally-directed recess 42 is provided in the front face of the frame 20 to the right of the recess 40, as shown particularly by FIG. 2. A shallow, arcuate recess 41 is formed in the front face of frame 20 above the level of the recess 40, and that recess is shown in FIG. 2. An opening 44 is provided in the frame 20 to the right of, and a short distance above the level of, the recess 42; shown particularly by FIG. 2. A vertically-directed opening 46, which has an arcuate upper end, is provided in the frame 20; and that opening is immediately adjacent the flange 24, as shown particularly by FIGS. 2 and 7. A generally horizontally-directed opening 48 is provided in the frame 20; and that opening is shown particularly by FIGS. 1, 2 and 7. A rib 50 is provided intermediate the openings 46 and 48, and that rib projects rearwardly from the rear face of the frame 20. The lower portion of the frame 20 has a thickened portion 52 which is shown in FIGS. 5 and 6. A threaded opening 54 is provided in the frame 20 below the level of the slot 36, as shown particularly by FIGS. 5 and 6.

The numeral 56 denotes a boss which extends forwardly from the front face of the frame 20, which is immediately adjacent the flange 24, and which is spaced a short distance below the upper edge of that frame. A short slot 58 is provided in the boss 56; and that slot opens to the front face as well as to the bottom face of that boss. A boss 60 extends forwardly from the front face of the frame 20; it is immediately adjacent the flange 24, and it is disposed below the level of the boss 56. A short slot 62 is provided in the boss 60; and that slot opens to the front face as well as to the upper face of that boss. Bosses 66 and 68 are provided on the rear face of the frame 20; and those bosses are disposed above the level of the slot 36, as shown particularly by FIG. 7. An opening 64 is provided in the frame 20 intermediate the bosses 66 and 68; and that opening is immediately adjacent the flange 24.

A shallow, circular recess 70 is provided in the front face of the frame 20, and that recess is shown particularly by FIG. 3. A disc 72 of magnetic material is dimensioned to fit within the recess 70; and that disc can be held within that recess by a rivet or some other fastener. A pivot 74 extends forwardly from the front face of the frame 20 adjacent the top edge of that frame; and that pivot rotatably supports a wiper blade 76. An actuator 78 is provided for the wiper blade 76; and that actuator has a camming surface 79 and a roller 80 thereon. A spring 82 encircles the pivot 74, it has one end thereof hooked under the boss 30, and it has the other end thereof hooked around the actuator 78 for the wiper blade 76. That spring biases that wiper blade to the position shown by FIGS. 1 and 2; but it can yield to permit rotation of that wiper blade in the clockwise direction about the pivot 74.

The numeral 84 denotes a deflector which has a rearwardly-projecting portion of reduced height that is disposed within the slot 36 in the frame 20. That deflector has a threaded opening therein which accommodates the shank of a screw 86; and the head of that screw is wider

than the slot 36 so it can abut the upper and lower edges of that slot and hold that deflector in position within that slot. Loosening of that screw permits shifting of that deflector toward and away from the flange 24. A rebounding surface 85 is provided on the deflector 84; and that rebounding surface coacts with the horizontally-directed bottom face of that deflector to subtend an angle of fifty-two degrees. The rebounding surface 85 will be hard and will be strongly resistant to wear caused by the engagement of coins or slugs with that surface. Specifically, the deflector 84 can be made of a hard material or the rebounding surface 85 can be specially hardened.

The numeral 88 denotes an anvil which is secured to the front face of the frame 20 adjacent the openings 44 and 46. That anvil has an inclined face at the top thereof, as emphasized particularly by FIGS. 1 and 2. That anvil can be made of hard material or that inclined face can be hardened. A large, generally rectangular plate 98 abuts the front face of the anvil 88; and nut and bolt combinations 89 secure that plate and that anvil to the frame 20. The plate 98 has an arcuate surface 99 which extends downwardly and forwardly through the opening 46 in the frame 20, as shown particularly by FIG. 5. The plate 98 also has a roughly-rectangular opening 100 therein; and that opening is in register with the recesses 40 and 42 plus a portion of the opening 44 in the frame 20, as shown particularly by FIG. 2. The plate 98 also has a lip 102 which inclines upwardly and rearwardly into engagement with the frame 20, as shown particularly by FIG. 6. A pivot 104 is mounted on the plate 98; and that pivot extends forwardly from the plane of FIG. 2. A gate 106 of bifurcated form is rotatably mounted on that pivot; and coin-engaging projections are provided on the ends of the arms of that gate. One of those projections extends into the recess 40 in the front face of the frame 20, while the other of those projections extends into the recess 41 in that front face. That gate is shown and described in Haverstick Patent No. 2,744,603 which was granted May 8, 1956 for Coin Separators. A runway 108 is formed on the front face of the plate 98, and that runway inclines downwardly from upper right to lower left in FIG. 2. That runway extends from a point adjacent the flange 24 to the lower left-hand corner of the plate 98.

The numeral 90 denotes a bracket which is generally L-shaped, as shown particularly by FIG. 7. That bracket has a horizontally-directed slot adjacent the upper end thereof; and a screw 92 extends through that slot and seats in the threaded opening 54 in the frame 20. The foot of the bracket 90 has a pivot 96 secured thereto; and that pivot rotatably supports a separator 94 which has a coin-receiving ear 95. That ear extends forwardly through the opening 48 in the frame 20, and it spans the coin-receiving passageway defined by the front face of the frame 20 and the rear face of the plate 98.

The numeral 110 denotes a large, roughly-rectangular plate which has ears 112 at the right-hand edge thereof; and those ears are disposed adjacent the flange 24. That plate has a small housing 114 thereon, and also has a small housing 116 thereon. Each of those housings encases and supports a permanent magnet; and the magnet within the housing 114 is denoted by the numeral 118. A slot 120 is provided in the plate 110; and that slot inclines downwardly at a shallow angle from upper left to lower right in FIG. 2. An ear 122 extends downwardly from the lower edge of the plate 110; and a set screw 124 is adjustably held within a threaded opening in that ear. That set screw and that ear overlie that portion of the plate 98 which helps define the upper edge of the opening 100 in that plate. The magnetic flux lines developed by the permanent magnet 118 and by the permanent magnet within the housing 116 coact with the disc 72 and with a similar disc adjacent housing 116 to bias the plate 110 toward the front face of the frame 20. The set screw 124 limits the movement of that plate toward that front face; and that set screw is adjusted so the plate 110 is normally substantially parallel to that front face. As a result, the plate

110 and the front face of the frame 20 coact to define part of a coin-receiving passageway.

The numeral 126 denotes a gate which has an elongated, horizontally-directed arm 128 at the upper edge thereof and which has an elongated, horizontally-directed arm 130 at the bottom edge thereof. Those arms extend toward the flange 24; and the right-hand ends of those arms are in register with the bosses 56 and 60 and with the ears 112 on the plate 110. A generally frusto-triangular coin-guiding member 132 is secured to, and projects upwardly from, the gate 126; and that coin-guiding member coacts with the coin-guiding member 27 on the frame 20 to define a coin entrance for the coin separator. The coin-guiding member 132 is secured to the gate 126 by a screw 134.

15 A pivot 136 extends vertically-upwardly from the arm 128 of the gate 126, and a roller 138 is rotatably mounted on that pivot. As shown particularly by FIGS. 1 and 2, that roller is immediately adjacent the camming surface 79 on the actuator 78 for the wiper blade 76. An arcuate notch 140 is formed in the left-hand edge of the gate 126; and that notch is immediately below the coin-guiding member 132. Part of that notch is in register with part of the arcuate recess 32 in the front face of the frame 20. An arcuate slot 142 is provided in the gate 126, below and to the right of the notch 140; and a notch 144 of generally-rectangular configuration is contiguous to the slot 142. An arcuate slot 146 is provided in the gate 126, below and to the left of the slot 142; and a straight slot 148 also is provided in that gate. The slot 148 communicates with the arcuate slot 146; and, as indicated by FIGS. 1 and 2, the slot 148 inclines sharply upwardly from lower left to upper right. A further arcuate slot 150 is provided in the gate 126 below the levels of the arcuate slots 142 and 146.

The numeral 152 denotes a pivot which is secured to and which projects forwardly from the front face of the gate 126. That pivot is adjacent the arcuate notch 140 and the arcuate slot 142, and it is concentric with that notch and that slot. A cradle 154 is rotatably mounted on that pivot; and one of the coin-receiving fingers of that cradle is disposed within the slot 140, while the other of those fingers is disposed within the arcuate slot 142. A feeler wire 156 has a portion thereof rotatably disposed within a groove in a boss, not shown, which is formed on the gate 126 adjacent the lower end of the arcuate slot 142. That boss and a plate, not shown, coact to maintain the feeler wire 156 in assembled relation with the gate 126 while permitting rotation of that feeler wire relative to that gate. A weight 158 is secured to the lower end of the feeler wire 156, and that weight biases the upper end of that feeler wire for movement into the upper portion of the arcuate slot 142.

50 Normally, however, the lower arm of the cradle 154 underlies the upper end of that feeler wire and keeps that upper end out of that slot.

The numeral 160 denotes another pivot which is mounted on the gate 126; and that pivot is adjacent, and concentric with, the arcuate slots 146 and 150. A cradle 162 is rotatably mounted on the pivot 160; and one of the coin-receiving fingers of that cradle extends into the arcuate slot 146, while the other of those fingers extends into the arcuate slot 150. A feeler wire 164 has a portion thereof rotatably disposed within a groove in a boss 167 which is provided on the front face of the gate 126 adjacent the lower end of arcuate slot 150. That boss and a plate 168 coact to maintain the feeler wire 164 in assembled relation with the gate 126 while permitting rotation of that feeler wire relative to that gate. A weight 166 is secured to the lower end of the feeler wire 164, and that weight biases the upper end of that feeler wire for movement into a slot, not shown, in the gate 126. Normally, however, the lower arm of the cradle 162 underlies the upper end of that feeler wire and keeps that upper end out of that slot. A coin-guiding member 170 is rotatably secured to an ear which is provided at the lower left-hand corner of the gate 126; and a weight 172 is secured to that guiding member. A portion of that guiding member

extends rearwardly into an opening, not shown, in the frame 20.

A runway 174 is provided on the rear face of the gate 126; and that runway is shown particularly by FIG. 2. That runway inclines downwardly at a shallow angle from upper left to lower right in FIG. 2; and it is in register with the slot 120 in the plate 110. The runway 174 is provided with a blunt discharge end 176; and that end contacts with a vertical line abutting the upper edge thereof to subtend an angle of ten degrees. As indicated particularly by FIG. 2, the blunt discharge end 176 inclines upwardly from lower left to upper right. A second runway 178 is provided on the rear face of the gate 126; and that second runway is below the level of the runway 174 and is adjacent the magnet housing 116. The blunt discharge end 176 of the runway 174 is hard so it can serve as a second rebounding surface and can strongly resist wear caused by the engagement of coins with that end. Specifically, the runway 174 can be made of hard material, the blunt discharge end 176 can be hardened, or that blunt discharge end can be faced with a hard material.

The numeral 180 denotes a knock-out plate which overlies part of the front face of the gate 126. That knock-out plate has a rectangular opening therein which is in register with the magnet housing 114. That knock-out plate also has ears which extend rearwardly therefrom and which have openings therein. Those ears are in register with the ears 112 on the plate 110, with the right-hand ends of the arms 128 and 130 of the gate 126, and with the slots 58 and 62, respectively, in the bosses 56 and 60. An elongated, vertically-directed pin 183 extends through an opening in the arm 128 of the gate 126, through an opening in the upper ear 112 of plate 110, through an opening in the upper ear of knock-out plate 180, through a helically-wound spring 184, through a helically-wound spring 186, through an opening in the lower ear of knock-out plate 180, through an opening in the lower ear 112 of plate 110, and through an opening in the arm 130 of the gate 126. That pin will serve as a pivot; and the upper and lower ends thereof will be lodged within the slots 58 and 62, respectively, in the bosses 56 and 58. One end of the spring 184 overlies an ear 182 on the knock-out plate 180; and the other end of that spring extends through the opening 64 in the frame 20. One end of the spring 186 overlies part of the gate 126; and the other end of that spring extends through the opening 64 in the frame 20. The springs 184 and 186 hold the pin 183 in assembled relation with the frame 20, and also bias the free edge of the gate 126 and the free edge of the knock-out plate 180 toward the frame 20. The runways 174 and 178 and an abutment on the rear face of the gate 126 engage the front face of the frame 20, and those runways and that abutment normally help keep the rear face of that gate substantially parallel to the front face of that frame. As a result, that gate and frame define the first part of the coin-receiving passageway which is defined, in part, by the plate 110 and the frame 20. An abutment, not shown, on the front face of the plate 110 normally holds "knock-out" ears on the free edge of the knock-out plate 180 out of the arcuate slot 142, out of the notch 144 contiguous to that slot, and out of the straight slot 148.

The numeral 188 denotes a wall which extends rearwardly from the rear face of the frame 20; and that wall is shown particularly by FIGS. 3-7. A partition 187 is spaced forwardly from the wall 188; and the upper edge of that partition inclines forwardly to underlie the lower edge of the arcuate surface 99 on the frame 20. The inclined upper portion of the partition 187 acts as an extension of that arcuate surface, as shown particularly by FIG. 5.

A cover plate 190 is suitably secured to the plate 98; and that cover plate normally overlies that plate. The right-hand edge of cover plate 190 extends to the flange 24 and the left-hand edge of that cover plate extends to

the flange 22. That cover plate coacts with the runway 108 to guide coins downwardly and to the left in FIG. 2.

The numeral 192 in FIGS. 8-14 signifies, and denotes the location of, an accepted coin chute. The numeral 194 in FIGS. 8-14 signifies, and denotes the location of, a rejected coin chute. In the embodiment of coin separator shown in FIG. 1, the rejected coin chute 194 is that portion of the coin passageway, defined by the plate 98 and the frame 20, which is disposed to the left of the coin-intercepting ear 95 on the separator 94. The accepted coin chute 192 is that portion of the said coin passageway which is intermediate that ear and the flange 24.

In many respects, the coin separator provided by the present invention is similar to standard and usual coin separators. However, in other respects, that coin separator is critically different from standard and usual coin separators. For example, that coin separator has two rebounding surfaces which are struck successively by higher resistivity coins. Thus, the coin separator shown in FIG. 1 has the rebounding surface 85 on the deflector 84, which serves as a first rebounding surface, and also has the blunt discharge end 176 on the runway 176, which serves as the second rebounding surface. Also, those rebounding surfaces are disposed so hard-surfaced, higher resistivity coins which successively rebound from them will enter the same accepted coin chute to which silver coins are directed. In addition, the rebounding surface 85 on the deflector 84 is inclined at an angle which causes a line, perpendicular to that rebounding surface and extending from the point where acceptable coins strike that surface, to extend above the level of that point on the second rebounding surface which will be struck by acceptable coins. Further, that second rebounding surface is inclined at an angle which causes a line, perpendicular to that second rebounding surface and extending from the point where acceptable coins strike that surface, to extend above the level of the separator.

The coin separator shown in FIG. 1 is intended to accept United States nickels, dimes and quarters. In addition, that coin separator is intended to accept coins which are similar to United States quarters but which are made of cupronickel. Such coins have resistivities which are materially higher than the resistivity of a United States quarter.

When a United States dime is introduced into the coin entrance defined by the coin-guiding members 27 and 132, that dime will be guided toward the cradle 154. Because that cradle is intended to intercept coins and slugs with diameters which equal or exceed the diameter of a quarter, the dime will fall freely between the coin coin-intercepting fingers of that cradle. The dime will then be directed toward the cradle 162; and, because that cradle is intended to intercept coins and slugs with diameters which equal or exceed the diameter of a nickel, the dime will pass downwardly between the coin-intercepting fingers of that cradle. The dime will then engage the rearwardly-extending portion of the coin-guiding member 170; and that portion will guide the dime rearwardly through an opening, not shown, in the frame 20. Thereafter, the dime will pass to testing and gauging components of standard and usual design which are mounted at the rear face of the frame 20. Subsequently, the dime will pass to the outlet chute defined by the thickened portion 52 of the frame 20 and the partition 187 shown in FIG. 5.

If a dime-size slug is inserted, it will pass between the coin-intercepting fingers of the cradles 154 and 162 and will then be directed rearwardly through the said opening, not shown, in the frame 20 by the coin-guiding member 170. Thereafter, that slug will be guided away from the outlet chute defined by the thickened portion 52 of the frame 20 and the partition 187 or will be intercepted and held. Where such a slug is intercepted and held, the patron who inserted that slug can effect the return thereof by pressing the scavenging button at the exterior 75 of the coin-operated device in which the coin separator

shown in FIG. 1 is mounted. The operation of the coin separator shown in FIG. 1 is, whenever a dime or a dime-sized coin or slug is inserted, not significantly different from the operation of other coin separators for dimes.

Whenever a United States nickel is introduced into the coin entrance defined by the coin-guiding members 27 and 132, that nickel will fall downwardly between the coin-intercepting fingers of the cradle 154 and be intercepted and held by the coin-intercepting fingers of the cradle 162. That cradle will rotate in the clockwise direction; and, as that cradle rotates, the upper end of the feeler wire 164 will respond to the weight 166 and move toward and engage the surface of the nickel. The nickel will be transferred to, and will roll along, the runway 178; and, as that nickel rolls off of the discharge end of that runway, it will pass through the magnetic flux lines provided by the permanent magnet within the housing 116. Because the resistivity of a nickel is relatively high, the eddy currents developed in the nickel will generate only a relatively small magnetic field; and hence the speed of the nickel will not be reduced materially. As a result, the nickel will rebound from the inclined face of the anvil 88 with sufficient force to pass to and through the space defined by the coin-engaging projections of the gate 106. Thereafter, the nickel will pass downwardly through the coin passageway defined by the plate 98 and the front surface of the frame 20 and pass to the space, intermediate the thickened portion 52 of that frame and the plate 98, which is shown in FIG. 5.

If a nickel-size washer is inserted, the upper end of the feeler wire 164 will intercept and hold that washer. Thereafter, the patron who inserted that slug can effect the return thereof by pressing the scavenging button at the exterior of the coin-operated device in which the coin separator shown in FIG. 1 is mounted. If a nickel-size slug of low resistivity is inserted, the eddy currents developed in that slug will generate a relatively large magnetic field; and hence the speed of that slug will be materially reduced. As a result, that slug will fall short of, or will gently strike, the anvil 88 and fall downwardly onto the lip 102 of plate 98; and that lip will guide that slug into the space between that plate and the cover plate 190. Thereupon, that slug will roll down the runway 108 and be returned to the patron who inserted it. If a nickel-size lead slug is inserted, that slug will strike the anvil 88 and will fall downwardly onto the lip 102 of plate 98; and that lip will guide that slug into the space between that plate and the cover plate 190. Thereupon, that slug will roll down the runway 108 and be returned to the patron who inserted it. Whenever a nickel or a nickel-size slug is introduced into the coin separator shown in FIG. 1, the operation of that coin separator is similar to the operation of other coin separators for nickels.

Whenever a United States quarter is introduced into the coin entrance defined by the coin-guiding members 27 and 132, it will be intercepted and held by the fingers of the cradle 154. That cradle 154 will start rotating from the position shown in FIG. 1 to the position shown in FIG. 2; and, as that cradle rotates, the weight 158 will urge the upper end of the feeler wire 156 inwardly into engagement with the quarter. The quarter will be transferred to, and will roll along, the runway 174; and then it will fall from the discharge end 176 of that runway. The eddy currents developed in the quarter, as it passes through the magnetic flux lines from the magnet 118, will cause the quarter to follow the path indicated by the dashed line 200 in FIG. 8. Specifically, the speed of the quarter will be retarded to such an extent that the quarter will not engage the deflector 84 but will engage, and pass to the right of, the ear 95 on the separator 94. The quarter will rotate the separator 94 from the solid-line to the dotted-line position shown by FIG. 8 as it engages and passes to the right of the ear 95. The quarter will then pass to the accepted coin chute indicated by the numeral 192 in FIG. 8.

If a quarter-size washer is inserted, the upper end of the feeler wire 156 will intercept and hold that washer. Thereafter, the patron who inserted that slug can effect the return thereof by pressing the scavenging button at the exterior of the coin-operated device in which the coin separator shown in FIG. 1 is mounted.

If a quarter-size coin of cupronickel is inserted, that coin will have a hard surface and will also have a resistivity higher than the resistivity of coin silver. Because of that relatively high resistivity, the eddy currents developed within that coin will be relatively small; and the magnetic field generated by those eddy currents also will be small. Consequently, the interaction between that magnetic field and the magnetic flux lines from the magnet 118 will not appreciably retard the speed of the coin. As a result, the coin will squarely engage the rebounding surface 85 on the deflector 84 and will rebound back toward the blunt discharge end 176 of the runway 174. That coin will squarely strike that blunt discharge end; and it will strike that blunt discharge end with sufficient force to rebound from that blunt discharge end and engage, and pass to the right of, the ear 95 on the separator 94. That coin will cause the separator 94 to rotate from the solid-line to the dotted-line position shown in FIG. 9, as it engages and passes to the right of the ear 95. This means that the coin will follow the path denoted by the dashed line 202 in FIG. 9 and will pass to the accepted coin chute 192. Significantly, the cupronickel coin as well as a quarter pass between the deflector 84 and the separator 94 and enter the accepted coin chute.

As indicated by the dashed line 202 in FIG. 9, the cupronickel coin squarely engages the rebounding surface 85 on the deflector 84 at a point above the lower edge of that rebounding surface. Thereafter, that coin squarely engages the blunt discharge end 176 of the runway 174 at a point spaced above the bottom edge of that discharge end. Finally, that coin rebounds through the space between the deflector 84 and the separator 94.

If a quarter-size copper slug was inserted and reached the runway 174, the eddy currents generated within that slug would be greater than the eddy currents generated within a quarter. Those eddy currents would develop a magnetic field which would interact with the magnetic lines of flux from the magnet 118 to retard the speed of the slug so materially that the slug would not reach the deflector 84; and, instead, would fall downwardly and pass to the left of the ear 95 on the separator 94. Consequently, that slug would be directed toward the rejected coin chute 194 by the separator 94. The path which would be followed by a copper slug passes well to the left of the deflector 84, and then engages and passes to the left of the ear 95 on the separator 94.

If a quarter-size zinc or brass slug was inserted, the eddy currents developed within that slug would be less than those generated within a quarter but would be greater than those generated within the cupronickel coin of FIG. 9. Those eddy currents would generate a magnetic field which would interact with the magnetic flux lines from the magnet 118 to retard the slug sufficiently to keep it from squarely engaging the rebounding surface 85 on the deflector 84. As a result, that slug would strike the lower left-hand corner of that deflector a glancing blow and then fall back toward and past the ear 95 on the separator 94. That slug would rotate the separator 94 from the solid-line position to the dotted-line position in FIG. 11 and then pass to the rejected coin chute 194. The path which would be followed by a zinc or brass slug is denoted by the dashed line 206 in FIG. 11.

If a quarter-size lead slug was inserted, the eddy currents developed within that slug would be materially smaller than those generated within a quarter; and hence the speed of that slug would not be materially reduced. As a result, that slug would squarely engage the rebounding surface 85 of the deflector 84—in much the same manner in which the cupronickel coin of FIG. 9 squarely

engaged that rebounding surface. However, because lead is relatively soft, the lead slug would not be able to rebound into engagement with the blunt discharge end 176 of the runway 174. Instead, that slug would fall back toward and past the ear 95 on the separator 94, and thus pass to the rejected coin chute 194. The path which would be followed by a lead slug is shown by the dashed line 208 in FIG. 12.

After the quarter of FIG. 8 or the cupronickel coin of FIG. 9 has passed between the deflector 84 and the separator 94, it will move downwardly through the coin passageway defined by the plate 98 and the front face of the frame 20 until it engages the arcuate surface 99. That surface will guide that quarter or coin through the opening 46 and into the space between the wall 188 and the partition 187; and, thereupon, that quarter or coin will pass to the cash box of the coin-actuated device in which the coin separator shown in FIG. 1 is mounted. Copper, zinc, brass, and lead slugs will pass to the left of the ear 95 on the separator 94, and will fall downwardly and engage the lip 102 adjacent the bottom of the opening 100 in the plate 98. That lip will guide those coins through that opening and into the space between the wall 98 and the cover plate 190. Those coins will then fall onto the runway 108, and will roll downwardly toward the flange 22 until they are free to fall into a chute, not shown, which will conduct them to a coin return receptacle at the exterior of the coin-actuated device in which the coin separator shown in FIG. 1 is mounted.

In the coin separator of FIG. 13, the magnet 118 has been shifted upwardly and to the left from the position which it occupied in FIG. 12. Also, the deflector 84 and the separator 94 have been shifted about one-sixteenth of an inch to the left. In all other respects, the coin separator of FIG. 13 can be identical to the coin separator shown in FIG. 1.

When a quarter-size hard-surfaced coin of relatively high resistivity, as for example a cupronickel coin, is inserted in the coin separator of FIG. 13, that coin will roll along the runway 174 without appreciable retardation and will squarely engage and rebound back from the rebounding surface 85 of the deflector 84. That coin will then squarely engage and rebound from the blunt discharge end 176 of the runway 174, and will engage and pass to the right of the ear 95 on the separator 94—thereby passing to the accepted coin chute 192. The path which will be followed by that coin is indicated by the dashed line 210 in FIG. 13; and that path is almost identical to the dashed-line path 202 in FIG. 9.

When a quarter is inserted in the coin separator of FIG. 13, that quarter will follow a path which is almost identical to the path indicated by the dashed line 200 in FIG. 8. Specifically, that quarter will fall short of the deflector 84 but will engage and pass to the right of the ear 95 on the separator 94. Whenever a quarter-size copper slug is inserted in the coin separator of FIG. 13, that slug will follow a path which is almost identical to the path indicated by the dashed line 204 in FIG. 10. Specifically, that slug will fall short of the deflector 84 and will engage and pass to the left of the ear 95 on the separator 94. Whenever a quarter-size zinc or brass slug is inserted in the coin separator of FIG. 13, that slug will follow a path which is almost identical to the path indicated by the dashed line 206 in FIG. 11. Specifically, that slug will strike the lower left-hand corner of the deflector 84 a glancing blow and fall back past and to the left of the ear 95 on the separator 94. Whenever a quarter-size lead slug is inserted in the coin separator of FIG. 13, that slug will follow a path which is almost identical to the path indicated by the dashed line 208 in FIG. 12. Specifically, that slug will squarely engage the rebounding surface 85 on the deflector 84 but will fall back past and to the left of the ear 95 on the separator 94. FIG. 13 thus demonstrates that minor changes in

the relative positions of the magnet 118 and of the runway 174 will not materially affect the operation of the coin separator.

In the coin separators of FIGS. 1 and 13, the second rebounding surfaces are formed on the discharge ends of the runways; and such an arrangement is desirable because it saves space and also minimizes the number of parts in the coin separator. However, as shown by FIG. 14, the second rebounding surface can be provided on a second deflector. Specifically, the coin separator of FIG. 14 has a second deflector 220 with a second rebounding surface 222 thereon; and that second deflector and that second rebounding surface are entirely independent of the runway 274. It will be noted that the rebounding surface 285 on the deflector 284 of FIG. 14 inclines upwardly at a steeper angle than does the rebounding surface 85 on the deflector 84 of FIGS. 1-13. However, the rebounding surface 285 is disposed so a line which is perpendicular to that surface and which passes through the point where acceptable coins engage that surface will pass above the level of that point on the rebounding surface 222 which is subsequently engaged by those coins. Further, it will be noted that the rebounding surface 222 is disposed so a line which is perpendicular to that surface and which passes through the point where acceptable coins engage that surface will pass above the level of the ear 295 on the separator 294 of FIG. 14.

When a quarter-size hard-surfaced coin of relatively high resistivity, as for example a cupronickel coin, is inserted in the coin separator of FIG. 14, that coin will roll along the runway 274 without appreciable retardation and will squarely engage and rebound back from the rebounding surface 285 of the deflector 284. That coin will then squarely engage and rebound from the rebounding surface 222 on the deflector 220, and will engage and pass to the right of the ear 295 on the separator 294—thereby passing to the accepted coin chute 192. The path which will be followed by that coin is indicated by the dashed line 225 in FIG. 14. As in the case of the coins shown in FIGS. 9 and 13, the coin shown in FIG. 14 moves in one direction above and beyond the dividing line between the accepted and rejected coin chutes to squarely engage and rebound from a first rebounding surface, moves back in the opposite direction above and beyond that dividing line to squarely engage and rebound from a second rebounding surface, and then again moves in the said one direction above and beyond that dividing line to pass to the accepted coin chute.

When a quarter is inserted in the coin separator of FIG. 14, it will roll along the runway 274 and be sufficiently retarded to fall short of the deflector 284 but to engage and pass to the right of the ear 295 on the separator 294. That quarter will follow a path which is very similar to the path 200 in FIG. 8. If a copper slug is inserted in the coin separator of FIG. 14, it will roll along the runway 274 and be retarded to such an extent that it will fall short of the deflector 284 and pass to the left of the ear 295 on the separator 294. That slug will follow a path which is very similar to the path 204 in FIG. 10. If a zinc or brass slug is inserted in the coin separator of FIG. 14, it will roll along the runway 274 and be retarded so little that it will strike the lower lefthand corner of deflector 284 a glancing blow and then fall back to engage and pass to the left of the ear 295 on the separator 294. That slug will follow a path which is very similar to the path 206 in FIG. 11. If a lead slug is inserted in the coin separator of FIG. 14, it will roll along the runway 274 and be retarded to such a small extent that it will squarely engage the rebounding surface 285 on the deflector 284. However, because that slug is relatively soft, it will fall back to engage and pass to the left of the ear 295 on the separator 294. That slug will follow a path which is very similar to the path 208 in FIG. 12. FIG. 14 thus demonstrates that the second rebounding surface can be spaced from the runway. Also, FIG. 14 demon-

strates that the rebounding surfaces can be set at different angles—even including an angle of ninety degrees.

In the coin separators of FIGS. 1-14, a silver coin, such as a quarter, and a quarter-size, hard-surfaced coin of higher resistivity, such as a cupronickel coin, have been accepted while copper, zinc, brass, and lead slugs have been rejected. However, the coin separators contemplated by the present invention are not limited to the acceptance of coins of any given size, and are not limited to the acceptance of silver coins and of coins of higher resistivity. Instead, the coin separators contemplated by the present invention can be used to accept coins of a given resistivity plus hard-surfaced coins of higher resistivity while rejecting slugs of intermediate and lesser resistivities and also rejecting relatively soft slugs of higher resistivity. In fact, the coin separators contemplated by the present invention can be used to reject quarters while accepting cupronickel coins; as by weakening the magnet 118 sufficiently to permit quarters to strike the rebounding surface 85 on the deflector 84 and then fall back to the left of the ear 95 on the separator 94 and pass to the rejected coin chute 194.

Whereas the drawing and accompanying description have shown and described several preferred embodiments of the present invention, it should be apparent to those skilled in the art that various changes can be made in the form of the invention without affecting the scope thereof,

What we claim is:

1. A coin separator that has:
  - (a) a runway along which coins and slugs can roll,
  - (b) said runway having a blunt discharge end,
  - (c) a source of magnetic flux lines adjacent said runway,
  - (d) a deflector that is spaced in one direction from said blunt discharge end of said runway and that can receive coins which successfully roll along, and then pass beyond said blunt discharge end of, said runway.
  - (e) said deflector having a rebounding surface thereon,
  - (f) said rebounding surface of said deflector being disposed below the level of said blunt discharge end of said runway,
  - (g) a separator that is spaced in said one direction from said blunt discharge end of said runway and is spaced in the opposite direction from said rebounding surface on said deflector,
  - (h) said separator being disposed below the level of said rebounding surface on said deflector and receiving coins which successively roll along, and then pass beyond said blunt discharge end of, said runway, and also receiving coins which successively roll along, and pass beyond said blunt discharge end of, said runway and then strike and rebound from said rebounding surface on said deflector,
  - (i) said rebounding surface on said deflector being disposed so a line which is perpendicular to that surface and which passes through the point where acceptable coins engage that surface will extend above the level of said blunt discharge end of said runway,
  - (j) said blunt discharge end on said runway being disposed so a line which is perpendicular to that end and which passes through the point where acceptable coins engage that end will extend above the level of said separator,
  - (k) an accepted coin chute, and
  - (l) a rejected coin chute,
  - (m) said accepted coin chute and said runway being oppositely disposed of said separator so a coin moving in said one direction from said blunt discharge end of said runway is moving toward said accepted coin chute,
  - (n) said rejected coin chute and said deflector being oppositely disposed of said separator so a coin moving in said opposite direction from said rebounding surface of said deflector is moving toward said rejected coin chute,

- (o) said runway guiding a coin or slug into said magnetic flux lines from said source of magnetic flux lines and permitting said coin or slug to roll off of said blunt discharge end thereof,
  - (p) said magnetic flux lines coaxing with the movement of said coin or slug to generate eddy currents in said coin or slug,
  - (q) said eddy currents in said coin or slug generating a magnetic field which interacts with said magnetic flux lines to tend to retard the movement of said coin or slug, whereby coins and slugs of different resistivities will roll along, and pass beyond said blunt discharge end of, said runway at different rates of speed,
  - (r) said deflector and said blunt discharge end of said runway being spaced apart sufficiently to enable some hard-faced coins that rebound from said deflector to fall short of said blunt discharge end of said runway,
  - (s) said deflector and said separator being positioned so a coin having a predetermined resistivity and which is moving in said one direction will be retarded sufficiently to pass between said deflector and said separator and enter said accepted coin chute without engaging either said deflector or said blunt discharge end of said runway,
  - (t) said deflector and said separator being positioned so a coin having a second and lesser predetermined resistivity and which is moving in said one direction will be retarded sufficiently to fall short of said deflector and to fall into said rejected coin chute without engaging either said deflector or said blunt discharge end of said runway,
  - (u) said deflector and said separator being positioned so a coin having a third and greater predetermined resistivity and which is moving in said one direction will strike said deflector and fall back in said opposite direction toward said separator and enter said rejected coin chute without engaging said blunt discharge end of said runway,
  - (v) said deflector and said separator being positioned so a hard-faced coin having a fourth and still greater predetermined resistivity and which is moving in said one direction will strike said rebounding surface of said deflector, will rebound back from said rebounding surface in said opposite direction, will strike said blunt discharge end of said runway, and will then rebound in said one direction to move between said deflector and said separator and pass to said accepted coin chute,
  - (w) said deflector and said separator being positioned so a soft-faced coin having a fifth predetermined resistivity and which is moving in said one direction will strike said rebounding surface of said deflector and will fall back in said opposite direction toward said separator and enter said rejected coin chute without engaging said blunt discharge end of said runway,
  - (x) whereby said coin separator can separate coins of said second predetermined resistivity, coins of said third predetermined resistivity, and soft-faced coins of said fifth predetermined resistivity from coins of the first said predetermined resistivity and hard-faced coins of said fourth predetermined resistivity,
  - (y) said coins of the first said predetermined resistivity being silver coins,
  - (z) said hard-faced coins of said fourth predetermined resistivity being cupronickel coins,
  - (aa) said deflector separating soft-faced coins from hard-faced coins, and said deflector coaxing with said blunt discharge end of said runway and with said source of magnetic flux lines to separate hard-faced coins of different resistivities.
2. A coin separator that has:
    - (a) a runway along which coins and slugs can roll,
    - (b) said runway having a blunt discharge end,
    - (c) a source of magnetic flux lines adjacent said runway,

- (d) a deflector that is spaced in one direction from said blunt discharge end of said runway and that can receive coins which successively roll along, and then pass beyond said blunt discharge end of, said runway, 5
- (e) said deflector having a rebounding surface thereon,
- (f) said rebounding surface of said deflector being disposed below the level of said blunt discharge end of said runway,
- (g) a separator that is spaced in said one direction from said blunt discharge end of said runway and is 10 spaced in the opposite direction from said rebounding surface on said deflector,
- (h) said separator being disposed below the level of said rebounding surface on said deflector and receiving coins which successively roll along, and then pass beyond said blunt discharge end of, said runway, and also receiving coins which successively roll along, and pass beyond said blunt discharge end of, said runway and then strike and rebound from said 15 rebounding surface on said deflector,
- (i) said rebounding surface on said deflector being disposed so a line which is perpendicular to that surface and which passes through the point where acceptable coins engage that surface will extend above the level of said blunt discharge end of said runway, 20
- (j) said blunt discharge end on said runway being disposed so a line which is perpendicular to that end and which passes through the point where acceptable coins engage that end will extend above the level of 25 said separator,
- (k) an accepted coin chute, and
- (l) a rejected coin chute,
- (m) said runway guiding a coin or slug into said magnetic flux lines from said source of magnetic flux lines and permitting said coin or slug to roll off of said blunt discharge end thereof, 30
- (n) said magnetic flux lines coating with the movement of said coin or slug to generate eddy currents in said coin or slug, 35
- (o) said eddy currents in said coin or slug generating a magnetic field which interacts with said magnetic flux lines to tend to retard the movement of said coin or slug, whereby coins and slugs of different resistivities will roll along, and pass beyond said blunt discharge end of, said runway at different rates of speed, 40
- (p) said deflector and said blunt discharge end of said runway being spaced apart sufficiently to enable some hard-faced coins that rebound from said deflector to fall short of said blunt discharge end of said runway, 50
- (q) said deflector and said separator being positioned so a coin having a predetermined resistivity and which is moving in said one direction will be retarded sufficiently to pass between said deflector and said separator and enter said accepted coin chute without engaging either said deflector or said blunt discharge end of said runway, 55
- (r) said deflector and said separator being positioned so a coin having a second and lesser predetermined resistivity and which is moving in said one direction will be retarded sufficiently to fall short of said deflector and to fall into said rejected coin chute without engaging either said deflector or said blunt discharge end of said runway, 60
- (s) said deflector and said separator being positioned so a coin having a third and greater predetermined resistivity and which is moving in said one direction will strike said deflector and fall back in said opposite direction toward said separator and enter said rejected coin chute without engaging said blunt discharge end of said runway, 70
- (t) said deflector and said separator being positioned so a hard-faced coin having a fourth and still greater 75

- predetermined resistivity and which is moving in said one direction will strike said rebounding surface of said deflector, will rebound back from said rebounding surface in said opposite direction, will strike said blunt discharge end of said runway, and will then rebound in said one direction to move between said deflector and said separator and pass to said accepted coin chute,
- (u) said deflector and said separator being positioned so a soft-faced coin having a fifth predetermined resistivity and which is moving in said one direction will strike said rebounding surface of said deflector and will fall back in said opposite direction toward said separator end enter said rejected coin chute,
- (v) whereby said coin separator can separate coins of said second predetermined resistivity, coins of said third predetermined resistivity, and soft-faced coins of said fifth predetermined resistivity from coins of the first said predetermined resistivity and hard-faced coins of said fourth predetermined resistivity,
- (w) said deflector separating soft-faced coins from hard-faced coins, and said deflector coating with said blunt discharge end of said runway and with said source of magnetic flux lines to separate hard-faced coins of different resistivities.
3. A coin separator that has:
- (a) a runway along which coins and slugs can roll,
- (b) a source of magnetic flux lines adjacent said runway,
- (c) a rebounding surface that is spaced in one direction from the discharge end of said runway and that can receive coins which successively roll along, and then pass beyond said discharge end of, said runway,
- (d) a second rebounding surface that is spaced in the opposite direction from the first said rebounding surface and that has a point thereon engageable by some acceptable coins,
- (e) a separator that is spaced in said opposite direction from the first said rebounding surface and is spaced in said one direction from said second rebounding surface and that receives coins which successively roll along, and then pass beyond said discharge end of, said runway, and that also receives coins which successively roll along, and pass beyond said discharge end of, said runway and then strike and rebound from the first said rebounding surface,
- (f) the first said rebounding surface being disposed so a line which is perpendicular to that surface and which passes through the point where acceptable coins engage that surface will extend above the level of said point on said second rebounding surface,
- (g) said second rebounding surface being disposed so a line which is perpendicular to that rebounding surface and which passes through said point where acceptable coins engage that rebounding surface will extend above the level of said separator,
- (h) an accepted coin chute, and
- (i) a rejected coin chute,
- (j) said accepted coin chute and said runway being oppositely disposed of said separator so a coin moving in said one direction from said discharge end of said runway is moving toward said accepted coin chute,
- (k) said rejected coin chute and the first said rebounding surface being oppositely disposed of said separator so a coin moving in said opposite direction from the first said rebounding surface is moving toward said rejected coin chute,
- (l) said runway guiding a coin or slug into said magnetic flux line from said source of magnetic flux lines and permitting said coin or slug to roll off of said discharge end thereof,
- (m) said magnetic flux lines coating with the move-

- ment of said coin or slug to generate eddy currents in said coin or slug,
- (n) said eddy currents in said coin or slug generating a magnetic field which interacts with said magnetic flux lines to tend to retard the movement of said coin or slug, whereby coins and slugs of different resistivities will roll along, and pass beyond said discharge end of, said runway at different rates of speed, 5
- (o) the first said and said second rebounding surfaces being spaced apart sufficiently to enable some hard-faced coins that rebound from the first said rebounding surface to fall short of said second rebounding surface, 10
- (p) the first said rebounding surface and said separator being positioned so a coin having a predetermined resistivity and which is moving in said one direction will be retarded sufficiently to pass between the first said rebounding surface and said separator and enter said accepted coin chute without engaging either of said rebounding surfaces, 15
- (q) the first said rebounding surface and said separator being positioned so a coin having a second and lesser predetermined resistivity and which is moving in said one direction will be retarded sufficiently to fall short of the first said rebounding surface and to fall into said rejected coin chute without engaging either of said rebounding surfaces, 20
- (r) the first said rebounding surface and said separator being positioned so a coin having a third and greater predetermined resistivity and which is moving in said one direction will strike said first said rebounding surface and fall back in said opposite direction toward said separator and enter into said rejected coin chute without engaging said second rebounding surface, 25
- (s) the first said rebounding surface and said separator being positioned so a hard-faced coin having a fourth and still greater predetermined resistivity and which is moving in said one direction will strike said first said rebounding surface, will rebound back from said first said rebounding surface in said opposite direction, will strike said second rebounding surface, and will then rebound in said one direction to move between the first said rebounding surface and said separator and pass to said accepted coin chute, 30
- (t) the first said rebounding surface and said separator being positioned so a soft-faced coin having a fifth predetermined resistivity and which is moving in said one direction will strike said first said rebounding surface and will fall back in said opposite direction toward said separator and enter said rejected coin chute, 35
- (u) whereby said coin separator can separate coins of said second predetermined resistivity, coins of said third predetermined resistivity, and soft-faced coins of said fifth predetermined resistivity from coins of the first said predetermined resistivity and hard-faced coins of said fourth predetermined resistivity, 40
- (v) said second rebounding surface being said discharge end of said runway, 45
- (w) the first said rebounding surface separating soft-faced coins from hard-faced coins, and the first said rebounding surface coating with said second rebounding surface and with said source of magnetic flux lines to separate hard-faced coins of different resistivities, 50
4. A coin separator that has:
- (a) a runway along which coins and slugs can roll, 70
- (b) a source of magnetic flux lines adjacent said runway,
- (c) a rebounding surface that is spaced in one direction from the discharge end of said runway and that can receive coins which successively roll along, and 75

- then pass beyond said discharge end of, said runway,
- (d) a second rebounding surface that is spaced in the opposite direction from the first said rebounding surface and that has a point thereon engageable by some acceptable coins,
- (e) a separator that is spaced in said opposite direction from the first said rebounding surface and is spaced in said one direction from said second rebounding surface and that receives coins which successively roll along, and then pass beyond said discharge end of, said runway, and that also receives coins which successively roll along, and pass beyond said discharge end of, said runway and then strike and rebound from the first said rebounding surface,
- (f) the first said rebounding surface being disposed so a line which is perpendicular to that surface and which passes through the point where acceptable coins engage that surface will extend above the level of said point on said second rebounding surface,
- (g) said second rebounding surface being disposed so a line which is perpendicular to that rebounding surface and which passes through said point where acceptable coins engage that rebounding surface will extend above the level of said separator,
- (h) an accepted coin chute, and
- (i) a rejected coin chute,
- (j) said runway guiding a coin or slug into said magnetic flux lines from said source of magnetic flux lines and permitting said coin or slug to roll off of said discharge end thereof,
- (k) said magnetic flux lines coating with the movement of said coin or slug to generate eddy currents in said coin or slug,
- (l) said eddy current in said coin or slug generating a magnetic field which interacts with said magnetic flux lines to tend to retard the movement of said coin or slug, whereby coins and slugs of different resistivities will roll along, and pass beyond said discharge end of, said runway at different rates of speed,
- (m) the first said and said second rebounding surfaces being spaced apart sufficiently to enable some hard-faced coins that rebound from the first said rebounding surface to fall short of said second rebounding surface,
- (n) the first said rebounding surface and said separator being positioned so a coin having a predetermined resistivity and which is moving in said one direction will be retarded sufficiently to pass between the first said rebounding surface and said separator and enter said accepted coin chute without engaging either of said rebounding surfaces,
- (o) the first said rebounding surface said separator being positioned so a coin having a second and lesser predetermined resistivity and which is moving in said one direction will be retarded sufficiently to fall short of the first said rebounding surface and to fall into said rejected coin chute without engaging either of said rebounding surfaces,
- (p) the first said rebounding surface and said separator being positioned so a coin having a third and greater predetermined resistivity and which is moving in said one direction will strike said first said rebounding surface and fall back in said opposite direction toward said separator and enter into said rejected coin chute without engaging said second rebounding surface,
- (q) the first said rebounding surface and said separator being positioned so a hard-faced coin having a fourth and still greater predetermined resistivity and which is moving in said one direction will strike said first said rebounding surface, will rebound back from said first said rebounding surface in said opposite direction, will strike said second rebounding surface, and will then rebound in said one direction to move between the first said rebounding surface and said separator and pass to said accepted coin chute,

- (r) the first said rebounding surface and said separator being positioned so a soft-faced coin having a fifth predetermined resistivity and which is moving in said one direction will strike said first said rebounding surface and will fall back in said opposite direction toward said separator and enter said rejected coin chute,
  - (s) whereby said coin separator can separate coins of said second predetermined resistivity, coins of said third predetermined resistivity, and soft-faced coins of said fifth predetermined resistivity from coins of the first said predetermined resistivity and hard-faced coins of said fourth predetermined resistivity,
  - (t) said second rebounding surface being separate from, and spaced below the level of, said discharge end of said runway,
  - (u) the first said rebounding surface separating soft-faced coins from hard-faced coins, and the first said rebounding surface coacting with said second rebounding surface and with said source of magnetic flux lines to separate hard-faced coins of different resistivities.
- 5 5. A coin separator that has:
- (a) a runway along which coins and slugs can roll,
  - (b) a source of magnetic flux lines adjacent said runway,
  - (c) a rebounding surface that is spaced in one direction from the discharge end of said runway and that can receive coins which successively roll along, and then pass beyond said discharge end of, said runway,
  - (d) a second rebounding surface that is spaced in the opposite direction from the first said rebounding surface and that has a point thereon engageable by some acceptable coins,
  - (e) a separator that is spaced in said opposite direction from the first said rebounding surface and is spaced in said one direction from said second rebounding surface and that receives coins which successively roll along, and then pass beyond said discharge end of, said runway, and that also receives coins which successively roll along, and pass beyond said discharge end of, said runway and then strike and rebound from the first said rebounding surface,
  - (f) the first said rebounding surface being disposed so a line which is perpendicular to that surface and which passes through the point where acceptable coins engage that surface will extend above the level of said point on said second rebounding surface,
  - (g) said second rebounding surface being disposed so a line which is perpendicular to that rebounding surface and which passes through said point where acceptable coins engage that rebounding surface will extend above the level of said separator,
  - (h) an accepted coin chute, and
  - (i) a rejected coin chute,
  - (j) said runway guiding a coin or slug into said magnetic flux lines from said source of magnetic flux lines and permitting said coin or slug to roll off of said discharge end thereof,
  - (k) said magnetic flux lines coacting with the movement of said coin or slug to generate eddy currents in said coin or slug,
  - (l) said eddy currents in said coin or slug generating a magnetic field which interacts with said magnetic flux lines to tend to retard the movement of said coin or slug, whereby coins and slugs of different resistivities will roll along, and pass beyond said discharge end of, said runway at different rates of speed,
  - (m) the first said and said second rebounding surfaces being spaced apart sufficiently to enable some hard-faced coins that rebound from the first said rebounding surface to fall short of said second rebounding surface,
  - (n) the first said rebounding surface and said separator being positioned so a coin having a predetermined
- 10 15 20 25 30 35 40 45 50 55 60 65 70 75

- resistivity and which is moving in said one direction will be retarded sufficiently to pass between the first said rebounding surface and said separator and enter said accepted coin chute,
- (o) the first said rebounding surface and said separator being positioned so a coin having a second and lesser predetermined resistivity and which is moving in said one direction will be retarded sufficiently to fall short of the first said rebounding surface and to fall into said rejected coin chute,
  - (p) the first said rebounding surface and said separator being positioned so a coin having a third and greater predetermined resistivity and which is moving in said one direction will strike said first said rebounding surface and fall back in said opposite direction toward said separator and enter into said rejected coin chute,
  - (q) the first said rebounding surface and said separator being positioned so a hard-faced coin having a fourth and still greater predetermined resistivity and which is moving in said one direction will strike said first said rebounding surface, will rebound back from said first said rebounding surface in said opposite direction, will strike said second rebounding surface, and will then rebound in said one direction to move between the first said rebounding surface and said separator and pass to said accepted coin chute,
  - (r) the first said rebounding surface and said separator being positioned so a soft-faced coin having a fifth predetermined resistivity and which is moving in said one direction will strike said first said rebounding surface and will fall back in said opposite direction toward said separator and enter said rejected coin chute,
  - (s) the first said rebounding surface separating soft-faced coins from hard-faced coins, and the first said rebounding surface coacting with said second rebounding surface and with said source of magnetic flux lines to separate hard-faced coins of different resistivities.
6. A coin separator that has:
- (a) a runway along which coins and slugs can roll,
  - (b) a source of magnetic flux lines adjacent said runway,
  - (c) a rebounding surface that is spaced in one direction from the discharge end of said runway and that can receive coins which successively roll along, and then pass beyond said discharge end of, said runway,
  - (d) a second rebounding surface that is spaced in the opposite direction from the first said rebounding surface and that has a point thereon engageable by some acceptable coins,
  - (e) a separator that is spaced in said opposite direction from the first said rebounding surface and is spaced in said one direction from said second rebounding surface and that receives coins which successively roll along, and then pass beyond said discharge end of, said runway, and that also receives coins which successively roll along, and pass beyond said discharge end of, said runway and then strike and rebound from the first said rebounding surface,
  - (f) the first said rebounding surface being disposed so a line which is perpendicular to that surface and which passes through the point where acceptable coins engage that surface will extend above the level of said point on said second rebounding surface,
  - (g) said second rebounding surface being disposed so a line which is perpendicular to that rebounding surface and which passes through said point where acceptable coins engage that rebounding surface will extend above the level of said separator,
  - (h) an accepted coin chute, and
  - (i) a rejected coin chute,
  - (j) said runway guiding a coin or slug into said magnetic flux lines from said source of magnetic flux lines and permitting said coin or slug to roll off of said discharge end thereof,
  - (k) said magnetic flux lines coacting with the movement of said coin or slug to generate eddy currents in said coin or slug,
  - (l) said eddy currents in said coin or slug generating a magnetic field which interacts with said magnetic flux lines to tend to retard the movement of said coin or slug, whereby coins and slugs of different resistivities will roll along, and pass beyond said discharge end of, said runway at different rates of speed,
  - (m) the first said and said second rebounding surfaces being spaced apart sufficiently to enable some hard-faced coins that rebound from the first said rebounding surface to fall short of said second rebounding surface,
  - (n) the first said rebounding surface and said separator being positioned so a coin having a predetermined

- lines and permitting said coin or slug to roll off of said discharge end thereof,
- (k) said magnetic flux lines coacting with the movement of said coin or slug to generate eddy currents in said coin or slug,
- (l) said eddy currents in said coin or slug generating a magnetic field which interacts with said magnetic flux lines to tend to retard the movement of said coin or slug, whereby coins and slugs of different resistivities will roll along, and pass beyond said discharge end of, said runway at different rates of speed,
- (m) the first said and said second rebounding surfaces being spaced apart sufficiently to enable some hard-faced coins that rebound from the first said rebounding surface to fall short of said second rebounding surface,
- (n) the first said rebounding surface and said separator being positioned so a coin having a predetermined resistivity and which is moving in said one direction will be retarded sufficiently to pass between the first said rebounding surface and said separator and enter said accepted coin chute,
- (o) the first said rebounding surface and said separator being positioned so a hard-faced coin having a greater predetermined resistivity and which is moving in said one direction will strike said first said rebounding surface, will rebound back from said first said rebounding surface in said opposite direction, will strike said second rebounding surface, and will then rebound in said one direction to move between the first said rebounding surface and said separator and pass to said accepted coin chute,
- (p) whereby said coin separator can accept coins of the first said predetermined resistivity and can also accept coins of said greater predetermined resistivity,
- (q) the first said rebounding surface separating soft-faced coins from hard-faced coins, and the first said rebounding surface coacting with said second rebounding surface and with said source of magnetic flux lines to separate hard-faced coins of different resistivities.
7. A coin separator that has:
- (a) a runway along which coins and slugs can roll,
- (b) a rebounding surface that is spaced in one direction from the discharge end of said runway and that can receive coins which successively roll along, and then pass beyond said discharge end of, said runway,
- (c) a second rebounding surface that is spaced in the opposite direction from the first said rebounding surface and that has a point thereon engageable by some acceptable coins,
- (d) a separator that is spaced in said opposite direction from the first said rebounding surface and is spaced in said one direction from said second rebounding surface and that receives coins which successively roll along, and then pass beyond said discharge end of, said runway, and that also receives coins which successively roll along, and pass beyond said discharge end of, said runway and then strike and rebound from the first said rebounding surface,
- (e) the first said rebounding surface being disposed so a line which is perpendicular to that surface and which passes through the point where acceptable coins engage that surface will extend above the level of said point on said second rebounding surface,
- (f) said second rebounding surface being disposed so a line which is perpendicular to that rebounding surface and which passes through said point where acceptable coins engage that rebounding surface will extend above the level of said separator,
- (g) an accepted coin chute,
- (h) a rejected coin chute,
- (i) said accepted coin chute and said runway being oppositely disposed of said separator so a coin moving in said one direction from said discharge end of said

- runway is moving toward said accepted coin chute,
- (j) said rejected coin chute and the first said rebounding surface being oppositely disposed of said separator so a coin moving in said opposite direction from the first said rebounding surface is moving toward said rejected coin chute, and
- (k) means to retard coins that roll along said runway and then fall from said discharge end of said runway,
- (l) said retarding means causing coins of the same hardness but of different properties to roll along, and pass beyond said discharge end of, said runway at different rates of speed,
- (m) the first said and said second rebounding surfaces being spaced apart sufficiently to enable some hard-faced coins that rebound from the first said rebounding surface to fall short of said second rebounding surface,
- (n) the first said rebounding surface and said separator being positioned so a coin of predetermined type which is moving in said one direction will be retarded sufficiently to pass between the first said rebounding surface and said separator and enter said accepted coin chute,
- (o) the first said rebounding surface and said separator being positioned so a coin of a second predetermined type which is moving in said one direction will strike said first said rebounding surface, will rebound back from said first said rebounding surface in said opposite direction, will strike said second rebounding surface, and will then rebound in said one direction to move between the first said rebounding surface and said separator and pass to said accepted coin chute,
- (p) the first said rebounding surface and said separator being positioned so a soft-faced coin which is moving in said one direction will strike said first said rebounding surface and will fall back in said opposite direction toward said separator and enter said rejected coin chute,
- (q) said coin of said predetermined type being a silver coin,
- (r) said coin of said second predetermined type being a cupronickel coin,
- (s) the first said rebounding surface separating soft-faced coins from hard-faced coins, and the first said rebounding surface coacting with said second rebounding surface and with said retarding means to separate hard-faced coins of different properties.
8. A coin separator that has:
- (a) a runway along which coins and slugs can roll,
- (b) a rebounding surface that is spaced in one direction from the discharge end of said runway and that can receive coins which successively roll along, and then pass beyond said discharge end of, said runway,
- (c) a second rebounding surface that is spaced in the opposite direction from the first said rebounding surface and that has a point thereon engageable by some acceptable coins,
- (d) a separator that is spaced in said opposite direction from the first said rebounding surface and is spaced in said one direction from said second rebounding surface and that receives coins which successively roll along, and then pass beyond said discharge end of, said runway, and that also receives coins which successively roll along, and pass beyond said discharge end of, said runway and then strike and rebound from the first said rebounding surface,
- (e) the first said rebounding surface being disposed so a line which is perpendicular to that surface and which passes through the point where acceptable coins engage that surface will extend above the level of said point on said second rebounding surface,
- (f) said second rebounding surface being disposed so a line which is perpendicular to that rebounding surface and which passes through said point where acceptable coins engage that rebounding surface will extend above the level of said separator,
- (g) an accepted coin chute,
- (h) a rejected coin chute,
- (i) said accepted coin chute and said runway being oppositely disposed of said separator so a coin moving in said one direction from said discharge end of said

75

- ceptable coins engage that rebounding surface will extend above the level of said separator,
- (g) an accepted coin chute,
- (h) a rejected coin chute,
- (i) said accepted coin chute and said runway being oppositely disposed of said separator so a coin moving in said one direction from said discharge end of said runway is moving toward said accepted coin chute,
- (j) said rejected coin chute and the first said rebounding surface being oppositely disposed of said separator so a coin moving in said opposite direction from the first said rebounding surface is moving toward said rejected coin chute, and
- (k) means to retard coins that roll along said runway and then fall from said discharge end of said runway,
- (l) said retarding means causing coins of the same hardness but of different properties to roll along, and pass beyond said discharge end of, said runway at different rates of speed,
- (m) the first said and said second rebounding surfaces being spaced apart sufficiently to enable some hard-faced coins that rebound from the first said rebounding surface to fall short of said second rebounding surface,
- (o) the first said rebounding surface and said separator being positioned so a coin of a second predetermined type which is moving in said one direction will strike said first said rebounding surface, will rebound back from said first said rebounding surface in said opposite direction, will strike said second rebounding surface, and will then rebound in said one direction to move between the first said rebounding surface and said separator and pass to said accepted coin chute,
- (p) the first said rebounding surface separating soft-faced coins from hard-faced coins, and the first said rebounding surface coating with said second rebounding surface and with said retarding means to separate hard-faced coins of different properties.
9. A coin separator that has:
- (a) a runway along which coins and slugs can roll,
- (b) a source of magnetic flux lines adjacent said runway,
- (c) a rebounding surface that is spaced in one direction from the discharge end of said runway and that can receive coins which successively roll along, and then pass beyond said discharge end of, said runway,
- (d) a second rebounding surface that is spaced in the opposite direction from the first said rebounding surface,
- (e) an accepted coin chute, and
- (f) a rejected coin chute,
- (g) said runway guiding a coin or slug into said magnetic flux lines from said source of magnetic flux lines and permitting said coin or slug to roll off of said discharge end thereof,
- (h) said magnetic flux lines coating with the movement of said coin or slug to generate eddy currents in said coin or slug,
- (i) said eddy currents in said coin or slug generating a magnetic field which interacts with said magnetic flux lines to tend to retard the movement of said coin or slug, whereby coins and slugs of different resistivity will roll along, and pass beyond said discharge end of said runway at different rates of speed,
- (j) the first said and said second rebounding surfaces being spaced apart sufficiently to enable some hard-faced coins that rebound from the first said rebounding surface to fall short of said second rebounding surface,
- (k) the first said rebounding surface being positioned so a coin having a predetermined resistivity and which is moving in said one direction will be retarded sufficiently to pass below said first said rebounding surface and enter said accepted coin chute,

- (l) the first said rebounding surface being positioned so a coin having a second and lesser predetermined resistivity and which is moving in said one direction will be retarded sufficiently to fall short of said first said rebounding surface and to fall into said rejected coin chute,
- (m) the first said rebounding surface being positioned so a coin having a third and greater predetermined resistivity and which is moving in said one direction will strike said first said rebounding surface and fall back in said opposite direction and enter said rejected coin chute,
- (n) the first said rebounding surface being positioned so a hard-faced coin having a fourth and still greater predetermined resistivity and which is moving in said one direction will strike said first said rebounding surface, will rebound back from said first said rebounding surface in said opposite direction, will strike said second rebounding surface, and will then rebound in said one direction to move below said first said rebounding surface and pass to said accepted coin chute,
- (o) the first said rebounding surface being positioned so a soft-faced coin having a fifth predetermined resistivity and which is moving in said one direction will strike said first said rebounding surface and will fall back in said opposite direction and enter said rejected coin chute,
- (p) whereby said coin separator can separate coins of said second predetermined resistivity, coins of said third predetermined resistivity, and soft-faced coins of said fourth predetermined resistivity from coins of the first said predetermined resistivity and hard-faced coins of said fourth predetermined resistivity,
- (q) the first said rebounding surface separating soft-faced coins from hard-faced coins, and the first said rebounding surface coating with said second rebounding surface and with said source of magnetic flux lines to separate hard-faced coins of different resistivities.
10. A coin separator that has:
- (a) a runway along which coins and slugs can roll,
- (b) a source of magnetic flux lines adjacent said runway,
- (c) a rebounding surface that is spaced in one direction from the discharge end of said runway and that can receive coins which successively roll along, and then pass beyond said discharge end of, said runway,
- (d) a second rebounding surface that is spaced in the opposite direction from the first said rebounding surface,
- (e) an accepted coin chute, and
- (f) a rejected coin chute,
- (g) said runway guiding a coin or slug into said magnetic flux lines from said source of magnetic flux lines and permitting said coin or slug to roll off of said discharge end thereof,
- (h) said magnetic flux lines coating with the movement of said coin or slug to generate eddy currents in said coin or slug,
- (i) said eddy currents in said coin or slug generating a magnetic field which interacts with said magnetic flux lines to tend to retard the movement of said coin or slug, whereby coins and slugs of different resistivities will roll along, and pass beyond said discharge end of, said runway at different rates of speed,
- (j) the first said and said second rebounding surfaces being spaced apart sufficiently to enable some hard-faced coins that rebound from the first said rebounding surface to fall short of said second rebounding surface,
- (k) the first said rebounding surface being positioned so a coin having a predetermined resistivity and

- which is moving in said one direction will be retarded sufficiently to pass below said first said rebounding surface and enter said accepted coin chute,
- (l) the first said rebounding surface being positioned so a hard-faced coin having a greater predetermined resistivity and which is moving in said one direction will strike said first said rebounding surface, will rebound back from said first said rebounding surface in said opposite direction, will strike said second rebounding surface, and will then rebound in said one direction to move below the first said rebounding surface and pass to said accepted coin chute,
- (m) whereby said coin separator can accept coins of the first said predetermined resistivity and can also accept coins of said greater predetermined resistivity,
- (n) the first said rebounding surface separating soft-faced coins from hard-faced coins, and the first said rebounding surface coating with said second rebounding surface and with said source of magnetic flux lines to separate hard-faced coins of different resistivities.

11. A coin separator that has:

- (a) a runway along which coins and slugs can roll,
- (b) a rebounding surface that is spaced in one direction from the discharge end of said runway and that can receive coins which successively roll along, and then pass beyond said discharge end of, said runway,
- (c) a second rebounding surface that is spaced in the opposite direction from the first said rebounding surface and that has a point thereon engageable by some acceptable coins,
- (d) a separator that receives coins which successively roll along, and then pass beyond said discharge end of, said runway, and that also receives coins which successively roll along, and pass beyond said discharge end of, said runway and then strike and rebound from the first said rebounding surface,
- (e) the first said rebounding surface being disposed so a line which is perpendicular to that surface and which passes through the point where acceptable coins engage that surface will extend above the level of said point on said second rebounding surface,
- (f) said second rebounding surface being disposed so a line which is perpendicular to that rebounding surface and which passes through said point where acceptable coins engage that rebounding surface will extend above the level of said separator, and
- (g) an accepted coin chute,

- (h) the first said and said second rebounding surfaces being spaced apart sufficiently to enable some hard-faced coins that rebound from the first said rebounding surface to fall short of said second rebounding surface,
- (i) the first said rebounding surface and said separator being positioned so a coin of predetermined type which is moving in said one direction will pass between the first said rebounding surface and said separator and enter said accepted coin chute,
- (j) the first said rebounding surface and said separator being positioned so a coin of a second predetermined type which is moving in said one direction will strike said first said rebounding surface, will rebound back from said first said rebounding surface in said opposite direction, will strike said second rebounding surface, and will then rebound in said one direction to move between the first said rebounding surface and said separator and pass to said accepted coin chute,
- (k) the first said rebounding surface coating with said second rebounding surface and with said separator to accept coins of the first said and said second predetermined types.

12. A coin separator that has:

- (a) a runway along which coins and slugs can roll,

75

- (b) a rebounding surface that is spaced in one direction from the discharge end of said runway and that can receive coins which successively roll along, and then pass beyond said discharge end of, said runway,
- (c) a second rebounding surface that is spaced in the opposite direction from the first said rebounding surface and that has a point thereon engageable by some acceptable coins,
- (d) a separator that receives coins which successively roll along, and then pass beyond said discharge end of, said runway, and that also receives coins which successively roll along, and pass beyond said discharge end of, said runway and then strike and rebound from the first said rebounding surface,
- (e) the first said rebounding surface being disposed so a line which is perpendicular to that surface and which passes through the point where acceptable coins engage that surface will extend above the level of said point on said second rebounding surface,
- (f) said second rebounding surface being disposed so a line which is perpendicular to that rebounding surface and which passes through said point where acceptable coins engage that rebounding surface will extend above the level of said separator, and
- (g) an accepted coin chute,
- (h) the first said and said second rebounding surfaces being spaced apart sufficiently to enable some hard-faced coins that rebound from the first said rebounding surface to fall short of said second rebounding surface,
- (i) the first said rebounding surface and said separator being positioned so a coin of predetermined type which is moving in said one direction will strike said first said rebounding surface, will rebound back from said first said rebounding surface in said opposite direction, will strike said second rebounding surface, and will then rebound in said one direction to move between the first said rebounding surface and said separator and pass to said accepted coin chute.
- (j) the first said rebounding surface and said separator being positioned so a coin of a second predetermined type will fall short of said first said rebounding surface and miss said accepted coin chute,
- (k) the first said rebounding surface coating with said second rebounding surface and with said separator to accept coins of the first said predetermined type while rejecting coins of said second predetermined type.
13. A coin separator that has:
- (a) a runway along which coins and slugs can roll,
- (b) a source of magnetic flux lines which is adjacent to said runway and which has an appreciable portion thereof disposed beyond the discharge end of said runway,
- (c) a rebounding surface that is spaced in one direction from said discharge end of said runway and that can receive coins which successively roll along, and then pass beyond said discharge end of, said runway,
- (d) an accepted coin chute, and
- (e) a rejected coin chute,
- (f) said runway guiding coins or slugs into said magnetic flux lines from said source of magnetic flux lines and permitting said coins or slugs to roll off of said discharge end thereof,
- (g) said magnetic flux lines co-acting with the movement of said coins or slugs to generate eddy currents in said coins or slugs,
- (h) said eddy currents in said coins or slugs generating magnetic fields which interact with said magnetic flux lines to tend to retard the movement of said coins or slugs, whereby coins and slugs of different resistivities will roll along, and pass beyond said discharge end of, said runway at different rates of speed,
- (i) said rebounding surface being positioned relative to

said discharge end of said runway so coins and slugs which have resistivities within a predetermined range and which have received a predetermined amount of retardation as they rolled through said magnetic flux lines will strike said rebounding surface and will rebound back toward said discharge end of said runway and pass through said appreciable portion of said magnetic flux lines,

- (j) said appreciable portion of said magnetic flux lines coating with the movement of said rebounding coins and slugs to generate further eddy currents in said coins and slugs,
- (k) said further eddy currents in said coins and slugs generating further magnetic fields which interact with

5

said appreciable portion of said flux lines to additionally retard the movement of said coins and slugs,

(l) the additional retardation of said coins and slugs coating with the initial retardation of said coins to guide said coins and slugs toward the appropriate chute.
